US00D903945S

(12) **United States Design Patent** (10) **Patent No.:** **US D903,945 S**
(45) **Date of Patent:** **** Dec. 1, 2020**

(54) **HELMET**

(71) Applicant: **ERB Industries, Inc.**, Woodstock, GA (US)

(72) Inventors: **Christopher T. Padgett**, Woodstock, GA (US); **Sheila M. Eads**, Woodstock, GA (US)

(73) Assignee: **ERB Industries, Inc.**, Woodstock, GA (US)

(**) Term: **15 Years**

(21) Appl. No.: **29/635,350**

(22) Filed: **Jan. 30, 2018**

(51) **LOC (12) Cl.** **02-03**

(52) **U.S. Cl.**

USPC **D29/102**

(57) **CLAIM**

The ornamental design for a helmet, as shown and described.

DESCRIPTION

FIG. 1 is a front perspective view of a helmet showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a rear perspective view thereof.

The broken lines in the drawings illustrate portions of the helmet that form no part of the claimed design.

1 Claim, 8 Drawing Sheets
